UNITED STATES PATENT OFFICE.

B. I. HARRIS, OF HARRISBURG, PENNSYLVANIA.

STOVE-PIPE DAMPER.

Specification forming part of Letters Patent No. **58,251**, dated September 25, 1866.

To all whom it may concern:

Be it known that I, B. I. HARRIS, of Harrisburg, in the county of Dauphin and State of Pennsylvania, have invented certain new and useful Improvements in Stove-Pipes for Saving Fuel; and I do hereby declare that the following is a full, clear, and exact description of the same, reference being had to the accompanying drawings, and to the letters of reference marked thereon.

In the annexed drawings, making part of this specification, A A represent two sections of an ordinary straight stove-pipe. A' A' represent two sections of pipe which are in the form of hollow frusta of cones, said frusta being joined together at their base.

The sections A A join the sections A' A' at their outer ends, as shown. The sections thus joined together are used as portions of stove-pipe on any ordinary stove.

Around the lower frustum, below its center, are a series of perforations or holes, b b, which admit cold air to the inside of the pipe. These perforations or holes may or may not be protected by the caps c c. It is not necessary that they should be protected, and if protected it will be more for ornament than for actual service.

B' represents an opening which is cut in the upper frustum, which said opening may or may not be provided with a door for closing it. As with the openings in the lower frustum, so with the opening in the upper—they both do best when left open and free to receive and admit external air.

The currents of air received through the openings or perforations b b pass in toward the center of the pipe; but being met by the current from door or opening B they are reversed and retarded and thrown from the center toward the sides of the pipe. This retard-

ing and reversing of the currents not only retards the combustion of the fuel in the stove, but serves to make the pipe receive and radiate more heat.

This invention on an ordinary stove will cause it to burn less fuel and yield more heat than without it.

Two stoves of the same construction and equal capacity have been tried for one month in a large building, one with and one without this pipe, and an accurate account kept of the amount of fuel consumed by each, and it has been ascertained from this experiment that the stove with my improved pipe consumes one-third less fuel, at least, and yields as much heat.

I have ascertained by actual experiment that a swelled joint, such as is shown, with two openings, or openings above and below the center of the joint, is necessary to produce the best results. One opening will not answer, neither will two openings, in a straight ordinary stove-pipe.

I do not claim the swelled joint of itself, nor do I claim making an opening in the side of a pipe for admitting air; but,

Having thus fully described my invention, what I do claim as new, and desire to secure by Letters Patent, is—

The swelled joint composed of the sections A' A', when the lower section is provided with perforations or holes, and the upper section with an opening or door, substantially in the manner and for the purpose herein specified.

In witness that I claim the foregoing I have hereunto set my hand in the presence of two witnesses.

B. I. HARRIS.
